(57) **CLAIM**

The ornamental design for an autoinjector with removable cap, as shown and described.

DESCRIPTION

FIG. 1 is a perspective view showing our new design for an autoinjector with a removable cap, showing the removable cap disposed on the autoinjector;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view showing the autoinjector with removable cap of FIG. 1 with the removable cap removed. The autoinjector is shown with symbolic breaks in its length. The appearance of any portion of the article between the break lines forms no part of the claimed design.
